RIGID FENDER FLAP

George Weasel, Jr., McClure, Ohio, assignor to Advance Industries, Inc., London, Ohio, a corporation of Ohio

Filed Oct. 4, 1965, Ser. No. 87,299

Term of patent 14 years

(Cl. D14—6)

FIG. 1

FIG. 2

FIG. 3

FIG. 4

FIG. 1 is a perspective view of the outer concave surface of a rigid fender flap embodying my new design.

FIG. 2 is a perspective view of the inner convex surface thereof.

FIG. 3 is a top plan view of the outer convex surface thereof.

FIG. 4 is a plan view of the right end of FIG. 3.

I claim:

The ornamental design for a rigid fender flap, as shown.
